UNITED STATES PATENT OFFICE.

JOSE M. ALMEDIA, OF SHOSHONE, IDAHO.

LOCKING DEVICE FOR BAGS.

1,295,834.

Specification of Letters Patent.

Patented Mar. 4, 1919.

Application filed May 22, 1918. Serial No. 235,991.

To all whom it may concern:

Be it known that I, JOSE M. ALMEDIA, a citizen of the United States, residing at Shoshone, in the county of Lincoln and 5 State of Idaho, have invented certain new and useful Improvements in Locking Devices for Bags; and I do hereby declare the following to be a full, clear, and exact description of the invention, such as will enable others skilled in the art to which it 10 appertains to make and use the same.

My invention relates to a locking device for bags.

An important object of this invention is 15 to provide a device of the character described having means for effectively closing the open end of a mail bag or the like.

A further object of this invention is to provide a device for effectively locking a 20 bag, which is easy to apply, reliable in use, of highly simplified construction and cheap to manufacture.

Other objects and advantages of the invention will be apparent during the course 25 of the following description.

In the accompanying drawing, forming a part of this specification, and in which like numerals are employed to designate like parts throughout the same:

30 Figure 1 is a side elevation of a bag having my improved locking device applied thereto,

Fig. 2 is a transverse section, taken on the line 2—2 of Fig. 1,

35 Fig. 3 is a side elevation of a rod adapted to extend through apertures in the bag, for the purpose of locking the same, and

Fig. 4 is a plan view of a pair of pivoted arms, forming a part of the invention.

40 In the drawing, wherein for the purpose of illustration is shown the preferred embodiment of my invention, the numeral 5 designates a cloth bag possessed of the usual degree of pliability. Apertures 6, formed 45 on opposite sides of the bag, are provided with metallic reinforcements 7 around their edges. As shown in Fig. 2, the upper portion of the bag is crimped to provide a plurality of U-shaped sections, thus alining the 50 apertures 6 for the reception of a rod 8 passing therethrough.

The rod 8 is secured to a U-shaped bracket 9 by a pivot 10. As shown in Fig. 3, the bracket 9 is U-shaped in cross section and 55 extends over opposite sides of the head 11 of the rod 8. The pivot 10 extending

through the bracket 9 and the rod 8 carries an eye 12, formed on one end thereof for the reception of a loop 13.

Arms 14, pivotally secured to the ends of 60 the U-shaped bracket 9, as at 15, are arranged parallel to the rod 8 and on opposite sides thereof. A lock 16 carried by the end of one of the arms 14 is adapted to co-act with a locking bar 17 pivotally secured to 65 the other arm 14, as at 18. An aperture 19, formed in the forward end of the pivoted rod 8 is adapted for the reception of the locking bar 17, extending therethrough. A depression 20 formed in the forward end of 70 the locking bar 17 is provided to permit of the functioning of the lock 16. It is obvious that any type of lock may be employed, this feature not being a part of the invention in the sense that any particular 75 type of lock must be employed.

In applying my improved locking device to mail bags, or the like, the rod 8 is passed through the alining apertures provided in the bag for this purpose. To lock the device, the locking bar 17 is passed through the aperture 19 in the forward end of the rod 8, and the end portion thereof is engaged by the lock 16. It is obvious that access to the bag is prevented through the 85 top portion thereof, without removing or demolishing the device.

While I have shown and described the preferred embodiment of my invention, it is understood that I may make such minor 90 changes in arrangement and construction of parts as will remain within the spirit of the invention and the appended claims.

Having thus described my invention, what I claim is:

1. The combination, with a bag formed of relatively pliable material and having apertures therein; the upper portion of said bag being crimped to form a plurality of U-shaped sections, thus alining the apertures 100 therein; a rod adapted to be passed through the alining apertures; a U-shaped bracket secured to one end of the rod; arms pivotally secured at one end thereof to the U-shaped brackets on opposite sides of said rod; and co-acting locking devices carried by the ends of the pivoted arms and adapted to prevent the removal of said rod from the alining apertures.

2. The combination, with a bag formed of 110 relatively pliable material, said bag having apertures in its upper end portion, said bag

being adapted to be crimped to form a plurality of U-shaped sections, thus alining the apertures therein; a rod adapted to extend through the alining apertures in the bag; a U-shaped bracket having pivotal connection with the rod; arms pivotally secured to the U-shaped bracket and arranged on opposite sides of said rod; a lock carried by one of said arms; a locking bar carried by the other pivoted arm and adapted to engage said rod and be engaged by the lock carried by the arms.

3. A locking device for bags comprising a rod having an opening in one end thereof, a bracket having pivotal connection with said rod at a central portion thereof, arms pivotally secured to the bracket, and locking devices carried by the ends of the arms and adapted to interlock, said locking devices including a locking rod and a lock, said locking rod being adapted to extend through the opening in the end of said rod.

4. The combination with a bag having

apertures in its upper end portion, said bag being adapted to be crimped to form a plurality of U-shaped sections, thus alining the apertures in the bag; a rod adapted to extend through the alining apertures, said rod having an opening in its forward end; a bracket formed substantially U-shaped in cross section; a pivot extending through the central portion of the bracket and the rear end of the rod for the purpose of effecting a pivotal connection; arms having pivotal connection with the forward end of the bracket and arranged parallel to the rod; a lock carried by one of said arms; and a pivoted locking rod extending through the opening in said first-named rod and engaging said lock.

In testimony whereof I affix my signature in presence of two witnesses.

JOSE M. ALMEDIA.
